STABILIZATION OF LIQUID ORGANIC CHLORINE COMPOUNDS

Leighton S. McDonald, Freeport, and Harris G. Hughes, Angleton, Tex., assignors to The Dow Chemical Company, Midland, Mich., a corporation of Delaware

No Drawing. Application November 6, 1957
Serial No. 694,718

5 Claims. (Cl. 260—652.5)

The present invention relates to stabilization of liquid organic chlorine compounds and more particularly relates to the inhibition of oxidation of polychlorinated hydrocarbons.

It has now been found that polychlorinated hydrocarbons can be stabilized against oxidation by the addition thereto of from 0.001 to about 1.0 percent by weight of a triaryl stibine having the formula

wherein each R represents phenyl or alkyl-substituted phenyl.

The following examples are illustrative of the present invention but are not to be construed as limiting.

Example 1

Eleven 200 milliliter aliquots of trichloroethylene containing various amounts of triphenyl stibine were heated at the reflux temperature (86.7° C.) for 16 and 48 hours, respectively. During this period, oxygen gas was continuously bubbled through the solution. The acidity of the solutions was taken before and after the heating period and the final color of the solution recorded. The following table reports the results of observations made at the times indicated.

Wt. Percent Triphenyl Stibine	Reflux Time, hrs.	Initial Acidity	Final Acidity, p.p.m.	Final Color
0	16	neutral	4,500	yellow.
0.001	16	do	113	water white.
0.01	16	do	10	Do.
0	48	do	7,560	yellow.
0.001	48	do	3,000	light yellow.
0.01	48	do	1,000	Do.
0.05	48	do	60	water white.
0.1	48	do	60	Do.
0.3	48	do	40	Do.
0.5	48	do	40	Do.
1.0	48	do	40	Do.

2
Example 2

In a similar manner as described in Example 1 employing 0.1 percent by weight of triphenyl stibine in perchloroethylene and refluxing the mixture at 120.8° C. for 24 and 48 hours continuously the following results were obtained.

10	Wt. Percent Stibine	Reflux Time	Initial Acidity	Final Acidity (percent)
0		24	neutral	0.1492
0.1		24	do	0.0186
0		48	do	0.3205
0.1		48	do	0.0215

Other aryl stibines which may be employed in accordance with the present invention are, for example, tribenzyl stibine, o-trityl stibine, m-trityl stibine, and p-trityl stibine.

We claim:

1. A stabilized polychloroethylene comprising polychloroethylene containing from 0.001 percent to about 1.0 percent by weight of a compound selected from the group consisting of triphenyl and alkyl substituted triphenyl stibine.

2. A stabilized trichloroethylene comprising trichloroethylene containing from 0.001 percent to about 1.0 percent by weight of a compound selected from the group consisting of triphenyl and alkyl substituted triphenyl stibine.

3. A stabilized perchloroethylene comprising perchloroethylene containing from 0.001 percent to about 1.0 percent by weight of a compound selected from the group consisting of triphenyl and alkyl substituted triphenyl stibine.

4. A stabilized trichloroethylene comprising trichloroethylene and from 0.001 percent to about 1.0 percent by weight of triphenyl stibine.

5. A stabilized perchloroethylene comprising perchloroethylene and from 0.001 percent to about 1.0 percent by weight of triphenyl stibine.
